NONREFILLABLE BOTTLE

Fabian K. Anderson, Buffalo, N. Y., assignor of thirty-three and one-third per cent to James Quinn and thirty-three and one-third per cent to Edward Regan, Buffalo, N. Y.

Application October 30, 1934, Serial No. 750,732

2 Claims. (Cl. 215—20)

The present invention relates to new and useful improvements in bottles in general and has for its primary object to provide, in a manner as hereinafter set forth, a bottle which may be readily emptied but which, after being emptied, cannot be refilled.

Another important object of the invention is to provide a non-refilling closure for bottles of the type including a reciprocating check valve, together with novel means for preventing tampering with said valve, as by the insertion of an instrument.

Other objects of the invention are to provide a bottle of the aforementioned character which will be comparatively simple in construction, strong, durable, highly efficient and reliable in use and which may be manufactured at low cost.

All of the foregoing and still further objects and advantages of the invention will become apparent from a study of the following specification, taken in connection with the accompanying drawing wherein like characters of reference designate corresponding parts throughout the several views, and wherein:

Fig. 1 is a view in vertical section through the neck portion of a non-refillable bottle constructed in accordance with the present invention.

Fig. 2 is a view in top plan thereof.

Fig. 3 is a view in horizontal section, taken substantially on the line 3—3 of Fig. 1.

Fig. 4 is a vertical sectional view through the stopper, taken substantially on the line 4—4 of Fig. 1.

Referring now to the drawing in detail, it will be seen that the embodiment of the invention which has been illustrated, comprises a stopper 5 which is mounted in the neck 6 of a bottle below the upper end of said neck, as seen in Fig. 1 of the drawing. The neck 6 and the stopper 5 have formed therein opposed grooves 7 and 8, respectively, for the reception of a split, resilient ring 9 which constitutes means for securing said stopper 5 in the neck. In assembling, the ring 9 is placed in the groove 8 and contracted for insertion in the bottle neck, said ring snapping into the groove 7 when the stopper reaches this point. Formed in the lower portion of the neck 6 is a flange 10 which provides a port 11 and a valve seat 12.

Depending from the stopper 5 is a stem 13 having spaced flanges 14 and 15 thereon providing annular channels 16. Extending into the stopper 5 from the top thereof is a socket 17 which communicates with the upper channel 16 through downwardly diverging ports 18. The flanges 14 and 15 have formed therein spaced peripheral

fluid passages 19, the passages 19 in the flange 14 being out of alignment with the ports 18 and the passages in the lower flange 15 for preventing the insertion of an instrument should it be attempted to tamper with the valve to be presently described.

The stem 13 is provided with a reduced lower end portion 20 which extends into the port 11 and terminates in a head 21, said reduced portion 20 providing a shoulder 22. Slidably and rotatably mounted on the reduced portion or shank 20 is a valve 23 of suitable material which is engageable on the seat 12 for closing the port 11 should it be attempted to refill the bottle.

It is believed that the operation of the invention will be readily apparent. When the bottle is being emptied, the liquid therein flows through the port 11, through the passages 19 and the channels 16, through the ports 18 and then through the socket or pocket 17 of the stopper 5. The valve 23 is readily disengaged from its seat 12 to permit the discharge of the liquid in this manner. However, should it be attempted to refill the bottle, the inflowing fluid seats the valve 23 for closing the port 11. Further, when the bottle is in an upright or a substantially upright position, the valve 23 engages by gravity on the seat 12. The shoulder 22 limits movement of the valve 23 toward open position. As hereinbefore stated, by reason of the fact that the passages 19 in the flange 14 are out of alignment with the ports 18 and the passages in the lower flange 15, the insertion of an instrument for the purpose of tampering with the valve 23 will be prevented.

The top of the head 21 is flush with the seat 12 and the valve 23 also seats on said head 21 in a manner to prevent leakage between said valve and the stem 20. The valve 23 is of buoyant material, preferably cork, and said valve possesses sufficient resiliency or elasticity to permit the same to be passed over the head 21. As illustrated to advantage in Figure 4 of the drawing, the retaining ring 9 is of polygonal cross section to conform to the grooves 7 and 8 and prevent longitudinal movement of the stopper 5 in the bottle neck. When expanded, the resilient ring 9 seats in the groove 7 but is also partially engaged in the groove 8.

It is believed that the many advantages of a non-refillable bottle constructed in accordance with the present invention will be readily understood, and although a preferred embodiment of the invention is as illustrated and described, it is to be understood that changes in the details of construction and in the combination and arrange-

ment of parts may be resorted to which will fall within the scope of the invention as claimed.

What is claimed is:

- 5 1. A non-refillable bottle comprising a neck, a valve seat in said neck, a stopper mounted in the neck having fluid passages therein, a stem depending from said stopper, a head on the lower end of said stem flush with the valve seat, and a valve slidable on the stem and engageable with the seat for preventing the flow of fluid into the bottle, said valve further being engageable with the head for preventing leakage between the stem and the valve.
- 10 2. A non-refillable bottle comprising a neck, a valve seat in said neck, a stopper mounted in the neck, a stem depending from said stopper, spaced

flanges on said stem having staggered fluid passages therein and defining annular channels, the stopper having a chamber extending downwardly thereinto and further having downwardly diverging parts establishing communication between said chamber and the uppermost channel, the stem including a reduced lower end portion providing a shoulder, a head on the lower end of said reduced portion flush with the seat, and a valve slidable on said reduced portion between the shoulder and the head and engageable with said seat for preventing the flow of fluid into the bottle, said valve further being engageable with the head for preventing leakage between the valve and the reduced portion of the stem.
